TRIMMER AND SLITTER

Merton L. Dodge, Seattle, Wash., and Ed Laxo,
Oakland, Calif., assignors to Continental Can
Company, Inc., New York, N. Y.

Application September 9, 1932, Serial No. 632,460

21 Claims. (Cl. 164—62)

This invention relates to machines for slitting and trimming sheets of tin plate or the like, especially for use in the making of can bodies; it being the principal object of the invention to provide a machine for the above purpose within which a stack of metal sheets may be placed, and in which machine, feed mechanism is provided for automatically removing the sheets from the top of the stack, one at a time, and for advancing them between cutters whereby they are divided first into strips, then the strips divided into blanks which are accurately sized for the making of can bodies.

More specifically stated, the objects of the present invention reside in the provision of a machine for trimming and slitting metal sheets and which has the following novel features:

First; a feed mechanism whereby the sheets of tin plate will be fed, one at a time, from the top of the supply stack, by the cooperative action of vertically reciprocating suction devices and a feed chain belt equipped with pushers for engaging the sheets, as lifted by the suction devices, to advance them to the slitting and trimming cutters.

Second; a stack elevator and means automatically operable to advance it upwardly in accordance with the decrease in the height of the stack incident to the feeding of sheets therefrom, thereby to maintain the top of the stack in proper position relative to the feed mechanisms.

Third; means for positioning and squaring up the sheets and strips relative to the cutters as they are delivered thereto.

Fourth; a hinged mounting for the sheet feed mechanism whereby it may be moved bodily to give easy access to the stack and also to the guideway for removal of damaged sheets, or for clearing the machine in the event of a jam.

Fifth; the provision of means for separating the several strips provided by passing a sheet through the first cutters, so that the strips may be taken up and advanced individually and successively to the cutters arranged for dividing them into blanks of definite length.

Sixth; the provision of a control valve of novel form for use in connection with the suction devices of the feed mechanism.

Seventh; the provision of automatic control and stop devices to preclude damage to the machine incident to jams or careless operation.

Other objects of the invention reside in the details of construction of the various parts, in their combination and in their mode of operation, as will hereinafter be described.

In accomplishing these objects, we have provided the improved details of construction, the preferred forms of which are illustrated in the accompanying drawings, wherein—

Fig. 1 is a plan view of a metal sheet trimmer and slitter embodied by the present invention. 5

Fig. 2 is a side elevation of the same.

Fig. 3 is a transverse section detail through the first set of cutting rolls and feed rolls.

Fig. 4 is the receiving end elevation of the machine. 10

Fig. 5 is a sectional view, of a part of the sheet feeding means, taken on line 5—5 in Fig. 1, particularly showing the suction cup mechanism for bowing the top sheet of the stack upwardly. 15

Fig. 6 is a sectional detail of the stack elevator control switch.

Fig. 7 is a detail, in side elevation, of a part of the feed mechanism as on line 7—7 in Fig. 5; showing the taking up of the top sheet from the stack by a hook on the feed chain. 20

Fig. 8 is an enlarged sectional detail, taken on line 8—8 in Fig. 7.

Fig. 9 is a sectional detail on line 9—9 in Fig. 1, showing means for separation of the strips as 25 they are delivered from the first series of cutters.

Fig. 10 is a similar view, illustrating the picking up and separating of strips by the conveyer chain which advances the strips to the second series of cutters. 30

Fig. 11 is a sectional detail, on the line 11—11 in Fig. 1.

Fig. 12 is a transverse section, substantially on the line 12—12 in Fig. 1.

Fig. 13 is a left end elevation, showing the driving means for the parts illustrated in Fig. 12. 35

Fig. 14 is an enlarged detail, in plan view of the "squaring up" means used in conjunction with the first series of cutters.

Fig. 15 is a cross section on line 15—15 in Fig. 14. 40

Fig. 16 is a plan view of the main control and driving clutch mechanism.

Fig. 17 is an elevation of the same.

Fig. 18 is an enlarged sectional detail of the 45 suction control valve.

Fig. 19 is a cross section of the same, on the line 19—19 in Fig. 18.

Fig. 20 is a diagrammatic illustration and wiring diagram of the automatic controls for the machine. 50

Fig. 21 is a detail of the automatic stop switch to be actuated by damaged sheets entering the machine. 55

Fig. 22 is a detail in elevation of the stack elevating pawl and ratchet mechanism.

Fig. 23 is a sectional view, substantially on line 23-23 in Fig. 22.

5 Fig. 24 is an end view of the mechanism of Fig. 22.

Fig. 25 is a detail of the stack elevator mechanism.

10 Fig. 26 is a detail of the automatic switch mechanism in connection with the elevator stop.

Fig. 27 is a detail of the safety lock.

Fig. 28 is a section on line 28-28 in Fig. 26.

The present machine includes a vertically movable elevator on which a stack of sheets of tin plate or the like, to be cut in pieces may be loaded. This elevator is automatically advanced upwardly to maintain the top of the stack in proper relation to a feeding mechanism whereby the sheets are picked up, one at a time, from the top 15 of the stack, and advanced along a guideway and against the first series of cutters. Automatically adjustable guides square up the sheets in their delivery so that the sheets will be properly trimmed and the dividing cuts will be square with respect 20 to the end edges.

25 The several strips, into which the sheets are initially divided, are advanced from the cutters across a second guideway that extends at a right angle to the direction of the first guideway and they are dropped into this guideway onto a conveyer chain operating centrally in and lengthwise thereof. Special means is provided for separating these strips as they are delivered from the first cutters, which permits them to be individually 30 picked up by lugs on the conveyer chain and advanced thereby to the second series of cutters which divide the strips crosswise into blanks exactly of proper size for can bodies. Means is also provided for properly locating the strips relative 35 to the last series of cutters to insure proper trimming.

40 The mechanism for feeding the sheets of tin plate into the machine from the top of the stack includes a pair of vertically movable suction cups which are arranged to be moved down against the top sheet of the stack, then to be moved upward while suction is applied to the cups to retain their hold on the sheet, so as to bow the center portion thereof upwardly for engagement by 45 hooks on an endless feed chain which operates to push the sheets to the squaring up means and into the first series of cutters. A special valve mechanism controls the timing and release of the application of suction to the cups, and special 50 means are also provided for automatically controlling the upward feeding of the stack, and for automatically disrupting the driving means of the machine in the event a jam should occur. Various devices are provided also for manual, as well 55 as automatic, control of the machine.

60 Referring more in detail to the drawings—

65 At the receiving end of the machine, which is the right hand end as seen in Fig. 1, is a frame structure which mounts the sheet feed mechanism and stack elevator. This frame, as seen best in Figs. 2 and 4, comprises a base structure formed by parallel I-beams 1 and 2, joined by cross frames 3. Erected on these base beams, approximately midway of their ends, are opposite 70 site side frames 4 and 5 of an upper structure providing an unobstructed open space between them within which a table 6 is located for the support of a stack of tin plate, as indicated in dotted lines at 7 in Figs. 2 and 4. The table is 75 used as a support and as an aid to loading the

stack into the machine and its construction provides that it may be moved into and from the machine on a small truck. As seen in Fig. 4, the table has flanges 7a-7a fixed to the frame thereof at opposite sides, adapted to be supported, respectively, upon angle iron beams 8 and 8' of the elevating mechanism. These beams are fixed, respectively, to brackets 9 and 9' through which vertical supporting shafts 10-10' are threaded. These shafts are revolvably supported at their upper and lower ends in suitable bearings, as at 10a, attached to the side frames 4 and 5 and are connected for rotation in unison to thereby raise or lower the stack.

10 For rotating the shafts 10-10', they are provided at their lower ends, respectively, with driving bevel gears 13 and 13' and meshing with these gears are bevel gears 14 and 14' fixed on the ends of shafts 15 and 15' which, respectively, extend lengthwise along the beams 1 and 2 and are revolvably supported in suitable bearings 16 and 17 as shown in Fig. 2. These latter shafts are connected, so that they may be rotated in unison, by a sprocket chain belt 18 which extends about sprocket wheels 19 and 19' on the shafts. Raising and lowering of the elevator is effected by rotation of shaft 15', and the means for doing this will later be described, after a description has been given of the driving mechanism.

15 The sheet feeding mechanism is carried by a frame structure 25, which, as seen best in Fig. 1, overlies the stack elevator between the side frames 4 and 5 and is swingingly supported for movement from a normal operative position, horizontally overlying the stack as seen in full lines in Fig. 4, to an upwardly inclined, open position as shown in dotted lines. The support about which the frame 25 is designed to swing is a shaft 26 that extends longitudinally along the top of the side frame 5. This shaft is revolvably driven by connection with the main driving mechanism of the machine, later described and is supported in bearings 27 fixed to the top rail of frame 5. A lever arm 28 is fixed to the frame 25 and extends outwardly to the side of the machine, as seen in Fig. 4. Attached to the arm and to a bracket 29 fixed to the base beam 2, is a coiled spring 30 the tension of which will lift and yieldingly retain the frame 25 in its raised position when released. A lever, or handle bar 31 is fixed to the frame 25 to extend from the swinging side thereof across the side frame 4 and this bar is used as a means for pulling the frame and feed mechanism down from raised position to horizontal functional position and it is designed to be locked in lowered position, thus to properly locate the feed mechanism relative to the stack. The lock consists of a link 32, having a seat 33 at its upper end to receive the bar, and pivotally fixed at its lower end by a bolt 34 to the frame 4. A hook 35 is pivotally attached to the link to overlie and retain the bar in the seat and when the hook is released from the bar, the spring 30 operates to swing the frame 25 and the feed mechanism to its raised position clear of the top of the stack.

20 When the stack of metal sheets is elevated to proper position for feeding the sheets therefrom to the first series of cutters, the top sheet of the stack will be disposed against a pair of parallel rollers 37-37' as seen in Figs. 4 and 5. These rollers are supported lengthwise of the direction of movement of the sheets to the cutters and are spaced apart a distance sufficient to permit of an 25

upward bowing of the top sheet between them. These rolls have pivots 37a at their ends revolvably contained in bearings 38 formed at the ends of supporting bars 39-39'. These bars extend 5 lengthwise of and above the rolls, as in Fig. 7 and are joined in parallel relation by cross bars 40 to which supporting posts 41-41' are centrally fixed; the posts being adjustably fixed in the frame 25 by set screws 43, or the like, to 10 permit of any desired or necessary vertical adjustment of the rollers.

In order that the sheets of tin plate, as they successively reach the top of the stack, may be bowed upwardly between the rollers 37-37' to 15 facilitate their being engaged by the attachment links of the feed chain, there is provided a pair of vertically movable suction devices, as illustrated best in Figs. 5, 6 and 7. These devices are located between the rollers 37-37' and are spaced 20 apart in a direction lengthwise of the movement of the sheet to the cutters. Each suction device, as seen in Fig. 5, consists of a tubular shaft 45 reciprocally movable in a supporting guide bracket 46 fixed to the outer rail 25a of the frame 25. Slidably fitted upon the lower end of each tubular shaft is a sleeve 47, formed at its lower 25 end with a downwardly opening, flexible suction cup 48 of rubber, or the like, which will be seated against the top sheet of the stack when its tube 30 is moved downwardly. On the upper end of each tubular shaft 45 is fixed a downwardly opening sleeve 49 which slidably fits over a tubular, upward extension 46a of the guide bracket 46 in which the tube slides. A rock shaft 50 is supported in brackets 51-51' on the frame 25 and to 35 this shaft, lever arms 52 are fixed. At their outer ends these arms have yokes 52' operatively connected, as at 52a, with the sleeves 49 for raising and lowering the tubular shafts 45 incident to 40 rocking action of shaft 50.

Fixed to one end of the rock shaft 50 is a lever arm 53 which, at its outer end, mounts a cam roller 54 arranged to follow within a cam groove 55 in a cam wheel 56 fixed on the shaft 26 so that, 45 with each turn of the shaft 26 the reciprocally mounted suction tubes will be actuated in unison first to move the suction cups 48 down against the top sheet in the stack of tin plate and then to lift upwardly; suction being applied to the cups 50 just as they are moved against the stack and maintained until they have been lifted. The suction applied within the cups holds the engaged sheet against them so that as they move upwardly, the sheet will be lifted and bowed upwardly between the rollers 37-37' as seen at 70 in Fig. 5.

Suction is applied to the cups 48 through the tubes 45 which are connected at their upper ends by flexible tubes 57 with the opposite ends of a pipe 58 which, in turn, has a pipe connection 58a, 60 intermediate its ends, with a suction control valve, designated at 59.

The valve 59 is co-axial of shaft 26 and, as seen 65 in Figs. 17 and 18, comprises a stationary outside housing 59a of frustro-conical form with an opening 60 at one side into which the pipe 58a is threaded. It also has a closing end wall 59b provided with a hub portion 59c adjustably clamped in a supporting bearing 27, as seen in 70 Fig. 17, and this hub has a central channel 61 into which a pipe 62, from a source of vacuum or suction, is threaded. Within the housing 59a, a rotary valve element 59d is fitted, and this element is operatively fixed to the end of shaft 26 to 75 rotate therewith.

This revolving valve element is mounted upon a hub-like extension 63 attached within the base of housing 59b co-axial thereof and provided with a channel 61a continuing from channel 61 and leading into a laterally opening pocket 64 in the revolving valve element. Each time the pocket 64 passes across the opening 60, suction will be communicated through the pipe system to the two suction cups, 48, and this takes place incident to each rotation of shaft 26. The rotary action of 10 the valve member is so synchronized with respect to the reciprocal action of the suction devices, that suction is applied just as the cups 48 move down against the top sheet of the stack and is maintained until the sheet has been lifted and 15 engaged by an advancing hook of the feed chain.

A feature in the construction of the suction devices is found in slidably mounting the sleeves 47 on the tubes 45, to provide a cushioning effect that prevents the hold of the cups being broken 20 from the sheets by reason of quick action of the tube actuating levers 52. It is to be observed, by reference to Figs. 5 and 8, that each sleeve 47 has a limited sliding movement on the lower end of its tube 45 and that it is held against disconnection therefrom by a link 64 which is attached at its upper end, to a collar 65 on the tube by a bolt 66 and at its lower end, has a shoulder 67 slideable in a vertical recess 68 in the sleeve. 25 As the tubes 45 are moved downwardly to locate 30 the suction cups against the top sheet of the stack, each sleeve is at its lower limit relative to its tube, but the application of suction to the cups is made just before the tubes 45 start to move upward and this causes an upward movement of the 35 sleeves on the tubes. This movement starts the upward bowing of the sheet before the tubes start actually on their upward movement. Then, when the tubes are actuated upwardly by the relatively quick action of levers 52, the internal suction 40 tending to retain the sleeves at their upper limits relative to the tubes, will operate to cushion the pull applied through the sleeves to lift and bow the sheet to the position 70 shown in Fig. 5. This cushioning effect prevents the quick upward 45 action of the tubes 45 from breaking the hold of the cups with the plate. However, after the initial upward movement, a positive connection between each tube and its sleeve 47 is effected 50 when the shoulder 67 of the connecting link engages against the upper end wall of the vertical recess 68 in the sleeve.

When the two suction devices move upwardly, the sheet of tin plate engaged is drawn upwardly between the rollers 37-37'. The rollers turn 55 freely in their supports so as to avoid any friction on the plate. Then, after the sheet has been bowed upwardly to the position shown in Fig. 5, it is advanced by the feed chain.

The feed chain 69 is of continuous belt form and 60 it extends about sprocket wheels 70 and 71. The sprocket wheel 70 is mounted by a stub shaft 72 adjustably fixed in one end of the frame 25 to provide for taking up slack in the belt, and the wheel 71 is fixed on a driving shaft 74 revolvably 65 supported in bearings 75-75 at the other end of the frame. The shaft 74 is provided at one end with a driving bevel gear 76 meshing with a bevel gear 77 keyed on the driven shaft 26.

The lower run of the feed chain extends horizontally 70 across the top of the stack of tin plate, parallel with and between the rollers 37-37', as seen in Figs. 5 and 7. At equal and definite intervals therealong, the chain is provided with attachments in the form of hooks, as at 80, de- 75

signed to hook over the rear edge of the upwardly bowed portion of the sheet, thereby to push it forwardly from the stack and into a guideway leading to the first series of cutters.

5 It will be mentioned here that the timing of the release of the suction on cups 48 and the picking up of the sheets by the advancing links 80 on the feed chain belt is very accurately adjusted so that the lifted sheets will be released 10 from the cups just as the forward end of the hook shank passes beneath the edge of the sheet, but before the base of the hook has actually engaged the sheet. This is done in order to prevent damage to the sheet, and also to avoid 15 frictional wear on the rubber suction cups by reason of slipping the sheet thereon. The hook shanks of course would be of sufficient length to provide for this result. The dotted line position 20 of hook 80 in Fig. 7 shows the position of the hook when suction is released.

A flat bed plate 82 extends between the side frames 4 and 5 and the sheets are advanced from the stack to the first series of cutters across this bed within a guideway formed between an angle iron rail 85 at one side and "squaring up" angle iron guides 86 and 87 at the other side. The opposite side edges of the advancing sheets will rest upon the base flanges of these angle bars and they will be guided by contact with their 30 vertical flanges. The bed plate 82 supports the tin sheets between the angle beams and, as seen in Fig. 7, this bed has a downwardly inclined forward edge portion 82a which aids in guiding the sheets onto the bed.

35 The proper position of the stack within the machine is determined partly by locating it within bolsters on the table 6 and by gauges or guide bars fixed in the frame structures and against which the stack is adjusted. As the stack is moved into position, the right hand vertical side surface, as seen in Figs. 2 and 4, is brought up against a pair of vertical guide bars 92 fixed to the side frame 5, and the forward end surface of the stack is adjusted up against a vertical stop bar 45 93 as seen in Fig. 2. The top sheets of the stack, immediately below the sheet that is picked up by the suction devices, are held against possible forward movement with the top sheet by a yieldable latch 94, as seen in Fig. 7. This latch is pivoted 50 at its lower end in the bed 82 by pin 95 and has a coiled spring 96 bearing thereagainst to urge it outwardly against the stack. At its upper end, the latch has a forwardly directed head 94a overlying the stack and this head has an upwardly 55 inclined under surface 97. When the top sheet is pulled up, it acts against the inclined surface and presses the latch back against the spring and out of the way. When the top sheet is released therefrom it snaps back into position to retain 60 the top sheets, not acted on by the feed chain, against possible forward movement by reason of frictional contact with the advancing sheet.

The action of the feed chain 69 is to slide the engaged sheet from the top of the stack onto the 65 bed plate 82, then between the stationary angle bar 85 and the squaring up angle bars 86-87 and deliver it to the first series of cutters. The upwardly bowed condition of the top sheet when in position for advancement decreases its normal width so that its entrance into the guideway is 70 made easy. The angle bar 85 is accurately located and fixed to bed 82 at a right angle to the axial line of the cutter arbors and each sheet is squared up relative to the cutters by bringing one of its 75 side edges firmly up against the angle bar 85 as

the sheet is advanced along the guideway. This squaring up is accomplished by the pressure exerted against the sheet toward bar 85 by the angle bar 86. The arrangement and operation of this will be best understood by reference to Figures 1, 14 and 15.

5 The two angle bars 86 and 87 are mounted by a bar 100 disposed lengthwise of the guideway upon the bed plate 82 and adjustably bolted thereinto. This bar is provided at its forward 10 end and at a point medially thereof with outward extensions 101-101' having slots 102 lengthwise thereof through which attaching bolts 103 are extended into the bed plate. Adjustment 15 of the width of the guideway is made by adjustment of bar 100 inwardly or outwardly and an adjustment is held by tightening the bolts. Angle bar 86 is located just within the bar 100 and it has a central, outwardly directed post or stud 104 slidable in a socket 104' in the bar 100. A 20 coiled spring 104a contained in the socket presses against the stud to urge the angle bar outwardly, that is, toward the opposite bar 85.

The angle bar 87 is pivotally attached by a 25 vertical pivot 105 to the end of bar 86 to serve as a continuation thereof, but it is outwardly inclined as seen in Fig. 1, to serve as a guide to direct the sheets of tin plate into the bar 86. At its receiving end, that is, the end nearest to the stack of tin plate, the bar 87 is attached by a 30 vertical pivot 106 to the mounting bar 100. While the angle bar 86 is permitted to move inwardly or outwardly, it is held absolutely parallel with bar 85 for all positions of adjustment, by the bar 87 and a link 107 that is connected pivotally at 35 its ends by pivot bolts 109 and 110 respectively, to the outer end portion of a bracket arm 111 fixed rigidly to bar 86 and a lateral arm 112 at the end of bar 100. This is a conventional parallel link mechanism and it operates to maintain 40 the bar 86 parallel with bar 85 under all inward or outward movement thereof provided for in its adjustable mounting. Therefore, when a sheet of metal is advanced by the feed chain, one side edge is brought up against angle bar 85, and the 45 opposite side edge is guided by bar 87 into engagement with the vertical flange of bar 86. The spring 104a urges angle bar 86 inwardly thereagainst to maintain the sheet squarely in position relative to the axial line of cutter arbors. Slight 50 variations in widths of different sheets is thereby taken care of in the yieldability of spring 104a without binding or bending the sheets.

As the sheets are successively advanced by the feed chain, along the guideway over bed plate 82, 55 they are pressed flatly thereagainst by bars 115 which overlie the bed lengthwise of the guideway. These bars are suspended from the frame 25 by links 116 pivotally attached to their forward ends and to the frame 25. At their rearward ends the 60 bars are designed to rest flatly against the sheets. Also, there are several downwardly inclined lever arms 118 fixed to a cross shaft 119 that is mounted rotatably in supports 120 in frame 25 and some of these lever arms are pivotally connected at their lower ends with the bars 115, and the others are provided with end shoes which ride upon and bear downwardly against the sheets passing thereunder to the cutters. These bars and levers operate to hold the sheets flatly 65 against the bed, but, in the event that a warped or buckled sheet enters the guideway, this will operate to raise one or more of the bars or levers, and in so doing will rotate the shaft 119. This 70 effects the opening of a switch in the automatic 75

electric control of the machine, thereby to disrupt the driving connection as will hereinafter be described in detail.

Alined with the rearward edge of the bed plate 5 82 are parallel arbors 122 and 123 on which the plate cutters 124 are fixed. The arbors are rotatably mounted at their ends in suitable bearings, as at 125, on the side frames 4 and 5, and they are connected for rotation in unison by intermeshing gears 126 and 127 fixed to ends thereof as seen in Fig. 2. The arbor 122 has a driving sprocket wheel 128 fixed thereon at one end through which connection is made by means of a sprocket chain belt 129 with a sprocket wheel 130 on a driven shaft 131.

The cutters 124 are of circular form, mounted on their arbors by hub portions 124a. The cutting peripheral portions of the cutters of the two arbors are arranged in overlapped, shearing relation, and as each sheet of tin plate is pushed forwardly by the feed chain and its forward edge moved against the cutters, it will be gripped thereby and carried ahead faster than the rate of travel of the feed chain, thereby freeing the rear edge of the plate from the hook of the feed chain.

As the sheets are delivered through the first series of cutters, the outer pairs of cutters trim the edges of the sheet, and the inner pairs of cutters divide the sheet into strips. The strips, on passing between the cutters, are picked up by a pair of feed rollers 134 and 135 located just rearwardly of the shearing rolls, as seen in Fig. 3, which deliver the strips into a second guideway extending at a right angle to the first guideway and leading to the second series of cutters.

These feed rolls are revolvably mounted at their ends in the frames 4 and 5 and are driven in unison by intermeshing gears 136 and 137 fixed on their ends, as seen in Fig. 2; gear 137 being driven by a gear 138 mounted on frame 4 and meshing with gear 127.

This second guideway is formed by a pair of angle bars 140-141 adjustably fixed upon a frame structure 142 erected upon the rearward ends of the I-beams 1 and 2 as seen in Figs. 1 and 2; this guideway being at a lower level than the first guideway, as seen in Fig. 2. Also, as noted by reference to Figs. 1, 9 and 10, cross rods 143 extend across the second guideway supported at their rearward ends in collars 144 adjustable along a supporting shaft 145 fixed at its ends in brackets 146 on the frame structure 142 and at their inner ends are adjustably fixed in a cross bar 147 mounted in the frame structure just rearwardly of the feed rolls 134-135, as seen in Fig. 3. These cross rods are so alined with the paired cutters of the first series that as the strips or sections of tin plate are delivered from the feed rolls, each strip will be supported closely adjacent its forward edge, as seen in Fig. 9, upon a cross rod and will travel thereon across the guideway until free of the feed rollers. When these strips are finally free of the feed rolls, they will drop into the guideway, and by reason of their forward edges overlying the cross rods, their rearward edges will drop first, as indicated by the dotted line showing thereof in Fig. 9, to aid in the separation of the strips.

Operating centrally of and lengthwise within the second guideway is a conveyer chain belt 148. This operates at its receiving end about a supporting sprocket wheel 149 revolvble on a stub shaft 149' fixed in a bracket attached to frame 142. At its other end it operates over

a sprocket wheel 150 keyed on a driven shaft 151. The top run of this chain belt is flush with the bottom of the guideway, and is supported in a channel member 152. The belt is provided at definite and regular intervals with attachment lugs 153 for pushing the strips forwardly along the guideway toward the second series of cutters.

The movement of the conveyer chain is so timed that the strips of tin plate designated by reference character 7b will drop onto it as shown in Fig. 10. That is, the forward edges of the strips will be supported on the lugs 153 and the rearward edges in positions resting on the chain or in position to be engaged by a lug at the rear edge. The ends of the strips will rest loosely within the angle guide 140-141 forming the guideway and the frictional contact by reason of weight, or drag, will cause the strips to slip back and thus position themselves between successive lugs of the conveyer chain as seen in Fig. 11. Thus, in this way, the strips 7b are separated for advancement successively to the second set of cutters.

It will be here stated that the angle beam 140 which forms one side of the guideway leading to the second series of cutters, is adjustably mounted upon supporting cross beams 142' of the frame structure 142 so as to provide for making the guideway wider or narrower. The supporting beams have longitudinal slots 154 therein, as seen in Fig. 1, and bolts 155 are extended through these slots and through the angle bar which, when tightened hold the adjustment of the bar. Also, the channel member 152 in which the conveyer belt 148 operates is adjustably supported at one end by a bracket 156 and at its other end is adjustably fixed to the bed frame; the support being adjustable in the frame structure in order to locate it centrally of the guideway, regardless of its width. It will be observed also, by reference to Fig. 1, that, a base plate 158 is located in the guideway between the channel member 152 and angle 140 to carry the ends of the strips delivered into this guideway across this space.

The second series of cutters is located in a frame structure 159 disposed at one side of the main frame and rigidly attached to the base beam 2 by an intermediate frame 160, as seen best in Fig. 4. This frame structure mounts two parallel arbors 162 and 163 on which cutters 164 and 165, like those of the first series, are mounted in overlapped shearing contact, as seen in Fig. 11. These two arbor shafts are connected to rotate in unison by means of intermeshing gears 166-167 fixed to their outer ends, and they are driven by a sprocket chain belt 170 which operates about a sprocket wheel 171 on the inner end of the arbor 162 and a sprocket wheel 172 on a driven shaft 173.

The driving means for the machine is an electric motor 175 bolted to a lateral extension of the frame 159, as seen in Figs. 1 and 4. A belt 176 operates about the motor pulley 177 and a belt wheel 178 on a shaft 179 that is rotatably mounted in bearings provided in the lateral extension of frame 159 one of which is indicated at 180, Fig. 1. The belt wheel 178 is operatively connected to shaft 179 through the medium of a clutch mechanism as at 181 and the clutch may be shifted to effect or to disconnect a driving connection by means of a lever 182 fixed to and supported by a vertical shaft 183 that is rotatable in a frame bracket 184. This control lever has a pivoted connection as at 185 with

the clutch collar for shifting the clutch. Also, there is a lever arm 186 fixed to shaft 183 and this is connected by a link 187 with a pivotally movable control lever 188 located at the opposite side of the machine so that an operator may have control also from that side.

Keyed on shaft 179 is a small gear 189 in driving mesh with a larger gear 190 keyed on the shaft 173. Also, shaft 173 has a geared connection, as seen in dotted lines at 192 in Fig. 1, with a cross shaft 193 mounted across the frame 159 parallel with shaft 151. A gear 194 on the rearward end of shaft 193 meshes with a gear 195 on shaft 151 thereby to provide a driving connection for the conveyer chain belt 148.

Also keyed on shaft 173 is a bevel gear 196 and this drives a bevel gear 197 keyed on the horizontal shaft 131 previously mentioned in the driving connection for the first series of cutters. Also, on shaft 173 is a sprocket wheel 198 alined with a sprocket wheel 199 on the end of shaft 26 and a sprocket chain belt 200 operates about these sprockets to drive the shaft 26 for operation of the feed mechanism which delivers the sheets of tin plate into the machine.

The conveyer chain belt 148 advances the strips received in the guideway to a position just forwardly of the second series of cutters. Then they are taken up by a pair of reciprocating feed slides which push them ahead of the chain lugs and on into the cutters. As seen best in Figures 1 and 11, the feed slides 205 are reciprocally contained in parallel guideways 206 at opposite sides of the conveyor chain. These slides 35 have downwardly yieldable push fingers 207 mounted in their upper edges. When the slides move rearwardly, these fingers yield downward to pass below the strip advanced by the chain, then as the slides are moved forwardly, they engage the rear edge of the strip to push it into the cutters.

The slides 205 are reciprocally actuated by means comprising a cam wheel 208 fixed on a supporting shaft 209 revolvable in a supporting bearing 210 attached to frame 159. This shaft is driven by a gear 212 which meshes with the driven gear 194 on the shaft 193. Mounted across the frame, below the cam wheel, is a rocker shaft 215 actuated by a rocker lever 216 fixed thereto and provided at its end with a cam roller 217 that follows within a slot 218 in the cam. Lever arms 219-219' are fixed to the rocker shaft to extend upwardly therefrom, and at their upper ends they are connected by links 220 with lugs 221 affixed to the slides. The driving connection is so constructed that the slides operate to pick up each of the strips as they are advanced by the conveyor chain, and to move them into the cutters; the action of the slides 60 being somewhat faster than the chain so as to clear the strips from the pushers on the chain.

It is very desirable in trimming these strips that they be accurately positioned relative to the cutters. This is especially true if the strips have 65 previously been lithographed. Accurate positioning is not insured simply by advancing the strips along the guideway, since it is necessary that they have a certain amount of looseness in the guideway to prevent binding. Also, the strips vary 70 in length and it is not possible to accommodate the guideway to the exact length of each strip. Therefore, we have provided means for causing each strip, just prior to its passing into the cutters, to be abutted squarely against the angle 75 iron guide 141 which extends clear up to the cut-

ters thereby to locate all strips accurately with respect to the cutters.

The strip positioning means consists of a slide bar 225, reciprocally contained within a guide bracket 226 attached to frame 159 at the side of the guideway opposite the guide channel 141, and it mounts the slide for reciprocal action toward and from the guideway. The slide bar is reciprocally actuated, in accordance with delivery of strips to the cutters, by the action of a lever 10 230 attached by a pivot bolt 231 to a support 232. The lever 230 is connected at its upper end, through a link 233, with a lug 234 on the slide, and is equipped at its lower end with a roller 235 that rides upon a cam track 236 adjustably 15 fixed on the outer face of gear wheel 212; this cam track being designed to cause the slide to move inwardly just as the feed slides move each strip up to the cutters. A coiled spring 238 attached to the lever and to the frame, holds the 20 lever to the cam track. Mounted on the slide 225 is an extension member 240, adjustably attached to the slide by bolts 241. At its outer end this extension has a downwardly directed member 242 designed by reason of inward travel 25 of the slide to abut against the end of each strip, as delivered by the feed slides, to push the strip over against the guide channel 141 thereby to accurately position and to square up the strip for delivery into the cutters. To take care of 30 slight differences in lengths of strips, the slide has a slight overrun, but a yieldable connection in link 233 permits the overrun without damage to the strip. The yieldable connection in link 35 233 is seen best in Fig. 12, which shows the slide 35 to be provided with a longitudinal slot containing a block 250 to which link 233 is attached. A spring 251 normally retains the block against one end of the slot, but on inward travel of the slide, after the roller 242 has abutted against 40 the end of a strip and pushed it over against the angle bar 141, the spring will yield to permit the slide to complete its travel without injury to the mechanism or strip.

To insure accurate squaring up of the strips 45 against the advancing lugs of the reciprocating feed slides, we have provided a friction finger 260, as seen in Fig. 11, to centrally engage the strips just before delivery to the cutters. This finger is pivotally mounted by a pin 261 in a bracket 262 50 attached to a cross bar 263 forwardly of the upper arbor 162. It extends in the direction of travel of the strips and is pressed downwardly by a coiled spring 264 held in the bracket. A friction pad 265 is held at the end of the finger to 55 engage the strips as they pass beneath it. In operation, should a strip be pushed forward by a pusher of a feed slide in a diagonal manner, the friction finger acts thereagainst as a sort of pivot by which the plate will be retarded in its 60 forward travel and about which it will be caused to adjust itself until pushed forward by lugs of both the feed slides, thereby causing the strip to pass squarely into the cutters.

As the strips are thus delivered through the 65 second series of cutters, they are cut into pieces of can body size. These pieces are carried through the cutter between upper and lower stripper plates 270 and 271 and then are taken up between feed rolls the upper one of which is indicated at 272, Fig. 1. These latter rolls are 70 revolubly supported at their ends in the frame structure and are driven by geared connection, as seen at 275 in Fig. 13 from the gear wheel 167.

As the pieces are delivered from between the 75

feed rolls, they are dropped into compartments 276 provided between series of plates 277 fixed vertically, in parallel relation upon a base frame structure 278 supported by brackets 279 upon the rear end of frame 159. Uprights 280 are aligned with the outer open ends of these separate compartments and these are all mounted on a cross shaft 281 which is bodily adjustable inwardly or outwardly in slots 282 in the brackets to accommodate blanks of different lengths.

To facilitate the removal of the stacks of blanks from the compartments, the uprights 280 are pivotally mounted on the cross shaft and may be swung outwardly and downwardly as seen in dotted lines in Fig. 4, to give easy access to the stacks. When released from this lowered position, the uprights will be pulled back to vertical position by coiled springs 285 attached to inward extensions 280a of the uprights and to the lower ends of arms 286 rigidly fixed to the cross shaft 281.

The means employed in connection with the machine driving mechanism for automatically adjusting the stack elevator upwardly as the sheets are used from the top of the stack, is understood best by reference to Figs. 20 to 28. As shown, the shaft 15' has a ratchet wheel 300 fixed to one end thereof, and adjacent this, a lever arm 301 is mounted on the shaft for an oscillating movement. A link 302 is connected at one end by a bolt 304 to this lever and at its other end is pivotally attached by a pin 302a eccentrically to the driving sprocket wheel 199 keyed on shaft 26. Thus, with each rotation of the sprocket the lever 301 is oscillated through a definite arc. A pawl 303 is pivotally mounted on the lever and is arranged to engage the ratchet to rotatably advance shaft 15' a definite amount each time the lever 301 swings upward. The lever arm has a plurality of openings 304' therealong for receiving the bolt 304 which connects it with link 302, so that by varying the point of connection, the angular movement of the lever may be made more or less as required to advance the stack to the feed devices faster or slower.

For automatic control of this stack feed mechanism, the pawl 303 is placed under control of a solenoid 306 mounted on an arm 301a integral with the lever 301, as seen in Fig. 24. A sliding core 306' in the solenoid is operatively connected with the pawl and so arranged that when the solenoid is energized, the pawl will be yieldingly drawn into engagement with the ratchet wheel for advancement thereof.

The solenoid is connected, as seen in Fig. 20, with a source of electrical energy, designated by the circuit mains M, through a main junction box 310. A circuit wire 311 leads from one side of the solenoid to a switch 312, and a connection 311a leads from the other side of the switch to the junction box 310 where it connects with one side of the circuit supply. A circuit wire 313 likewise leads from the other side of the solenoid to one side of a control switch 314, used in connection with automatic control of the stack feed mechanism, later described, and the other side of this latter switch is connected by a wire 315 with one side of a second control switch 316. The other side of switch 316 has a circuit wire 317 leading therefrom to the junction box 310 where it connects with the other side of the source of electricity to complete the solenoid circuit.

Thus to close a circuit through the solenoid 306, both switches 314 and 316 must be closed. Assuming that switch 316 is closed, as in normal op-

eration, then the action of solenoid 306 for actuating the pawl 303 into and from the ratchet 300 is under control of switch 314. This switch, as seen in detail in Fig. 6, consists of the conventional form of mercury tube 320 supported by a rocker 321 pivotally mounted on a pin 322 for endwise tilting of the tube. The circuit wires 313 and 315 enter one end of the tube and when the tube is tilted toward that end, the mercury in the tube effects an electrical connection between the wires to close the circuit. Tilting in the opposite direction opens the circuit. The switch tube is actuated under control of a lever arm 325 mounted by a pivot 325a on a bracket 326 that is fixed to and extends downwardly from the frame 25. The upper end of lever 325 is longitudinally slotted, at 327, and this slot slidably contains a pin 328 that extends from the lower end of the switch supporting rocker 321. Another lever 329 is pivotally mounted by pivot 325a to extend substantially at right angles to lever 325 and this has a post 329' adjustably mounted at its end to be engaged by the top sheet of the stack of tin plate as the stack is moved upwardly, thereby to rock the lever 329 accordingly. Movement of lever 329 is transmitted to lever 325 by a coiled spring 330 that is interposed between mounting lugs 330a and 330b therefor on the two levers. Thus, when the stack of tin plate is moved upwardly against the post 329', it rocks lever 329, and this causes lever 325 to rock the switch tube 320 on its mounting to open the circuit therethrough. This de-energizes solenoid 306, and the pawl 303 moves free of ratchet 300 to temporarily discontinue the upward feeding of the stack.

After the stack has been lowered sufficiently by the feeding of sheets of tin from its upper end that the lever 329 may move downwardly, then the switch tube 320 is rocked back to close the circuit and again cause an upward feeding of the stack. As seen in Fig. 6, a coiled spring 331, attached to lever 325 and to the bracket 326, operates to move the switch to closed position when pressure exerted through the lever 329 and spring 330 is released.

In order that the stack elevator will not continue in its upward travel after the sheets of tin have all been used therefrom, and there is nothing to actuate the lever 329', we have provided means for automatically opening the circuit switch 316 thereby to open the solenoid circuit and discontinue the upward feeding action of shaft 15'. This automatic means consists of a vertical rod 332 slidably supported in guide bearings 333-333' at upper and lower ends. At its lower end the rod has a laterally extended forked arm 334, as seen in Figs. 26 and 28, arranged to engage a pin 335' in a rocker lever 335, thus to move the switch 316 to open the circuit therethrough, and at its upper end the rod has a collar 336 fixed thereon to be engaged by a forked bracket 337 fixed to the elevator. The collar is so positioned that, as the elevator moves to its upper position, it is engaged by the bracket 337 and this lifts the rod to cause arm 334 to engage the pin 335' of rocker arm 335 thus to open the switch 316, thereby breaking the solenoid circuit and stopping any farther upward feeding of the elevator.

The lowering of the elevator mechanism, for placing a new stack of tin plate in the machine, is accomplished by an electric motor 338. This has a gear 339 on its shaft in mesh with a gear 340 keyed on the elevator adjusting shaft 15'. The motor is mounted on one of the lower frame members and it has a circuit connection 341 from

one side to a control switch 342, and a wire 341 connects the other side of this switch with the source of electricity in the junction box 310. Likewise, a wire 343 leads from the other side of the motor to a switch 344 closely associated with switch 316. A wire 343' connects the other side of this latter switch with the other side of the source of electricity in box 310. Thus, when both switches 342 and 344 are closed, the motor 338 will operate to rotate shaft 15' in a direction for lowering the stack elevator.

The main control switch 312 for the sheet feed mechanism and the switch 342 are under control of a hand lever 348 that is pivotally mounted on shaft 15'. When this lever is in a lowered position, as in Fig. 20, switch 312 is closed and switch 342 is open. To accommodate both switches to the same control device, they are arranged close together as in Fig. 22. Each switch consists of the conventional form of mercury tube, and these are mounted on a pivot shaft 346 in a switch housing 347. Switch 312 has a trip arm 312a and switch 342 has a control arm 342a. The switch control lever 348 has two arcuate cam surfaces 348a and 348b and an abutment 348c. In normal operation of the machine, lever 348 is lowered, as in Fig. 20. When the lever is pulled upwardly from lowered position to set the motor 338 in motion, the cam surface 348a engages with a pin 303' extended laterally from pawl 303 to hold it disengaged from its ratchet. Also, the cam surface 348b engages the depending switch trip arm 312a of switch 312 to rock the switch tube to open the circuit of solenoid 306. When the lever 348 is completely raised, the stop 348c engages the trip arm 342a of switch 342 and rocks this switch to close the circuit of motor 338 to cause the lowering of the elevator. When the elevator has been lowered to a desired position, lever 348 may be pushed down an initial distance to release switch arm 342a to open the motor circuit thus to stop farther lowering. A further movement of the lever 348, back to initial position, permits switch 312 to close and pawl 303 to be released.

As an automatic cut out of the motor 338 to prevent the elevator mechanism being inadvertently lowered too far, we have provided a stop collar 350 on the lower end of rod 332. This collar will be engaged by the forked arm 337 on the elevator as the latter approaches its lower limit, then the rod will be moved downwardly thereby. An arm 351 extends laterally from the lower end of the rod 332 in position to engage with a switch actuating, or trip lever 352 of switch 344 to actuate the switch to open the motor circuit. This operation is illustrated in Figs. 26 and 27.

Briefly described, the arrangement of switches 316 and 344, as shown in Fig. 26, is as follows. Each switch is the conventional form of mercury tube with circuit connections entering one end. The two tubes are pivotally mounted in a cross rod 353 in a housing 354. Each tube is actuated in a direction to open its circuit by its respective lever, 335 and 352 and the arms 334 and 351 in the lower end of rod 332. Coiled springs 355 attached to the tube mountings and to the switch housing operate to rock the switches back to a position, when released, to close the circuits.

After the elevator has been lowered, and a stack 70 of tin plate placed thereon, it is customary for the operator to fit a crank, as at 360 in Fig. 20, on the upper end of shaft 10' and to wind it up to bring the stack into proper position relative to the suction devices 48 for feeding. Should it happen 75 that this adjustment was made while the lever 348

was in raised position, the switch 344 would close as soon as the elevator had moved upward a distance sufficient to clear the bracket 337 from the collar 350, and this would cause the motor 338 to be thrown into operation while the operator was using the crank. In order to prevent this undesirable occurrence, we have provided a safety lock mechanism consisting of a shaft 365 which extends parallel with shaft 15', as seen in Fig. 20, and which is revolute in supports as at 366. An arm 367 is fixed to one end of this shaft and this arm is connected by a link 368 to lever 348 so that when the latter lever is raised or lowered, the shaft 365 is rotated accordingly. On the other end of the shaft is a pivotally mounted latch 370 urged upwardly by a spring 371 as seen in Figure 27. When the lever 348 is moved to a raised position, to close the switch 342, the shaft 365 is rotated to a position to place the latch 370 in the path of movement of switch arm 352. Then when the arm 351 moving downwardly actuates the arm 352 to open the switch 344, it snaps back of the latch 370 and the switch is thus held open. Thus, the circuit of motor 338 can not be closed inadvertently, but only after lever 348 has first been lowered and then brought back to raised position.

The mechanism for automatically disrupting the main driving clutch of the machine in the event that a jam should occur in feeding sheets into the first series of cutters, or in the event that a warped or damaged sheet should be advanced across the bed 82 to the cutters, is best understood by reference to Figs. 16 and 17 taken with the diagrammatic view of Fig. 20.

As was previously explained, should a jam occur in feeding a sheet of tinplate to the first set of cutters, or should a warped sheet enter, beneath the bars 115 and 118 which overlie the bed plate 82, this will raise the bars upwardly and thereby partially rotate the cross shaft 119 with which they are connected. On this shaft is mounted a lever arm 400 which, as seen in Fig. 21, extends upwardly and into a switch box 401 fixed to frame 25. Within this box is a mercury tube switch 402 mounted by a pivoted rocker 403 provided at a point below its mounting pivot 404 with a stud 405 disposed within a slot 406 in the end of the lever arm. The mercury tube has circuit connections 409 and 410 leading into one end thereof and when the tube is tilted in that direction, the mercury will electrically connect them.

Mounted on the vertical shaft 183 by which the clutch lever 182 is supported, is a bracket 412 on which a solenoid 413 is mounted. This is connected at one side with the source of electricity in junction 310 by a wire 415 and its other side is connected to the source of current by wires 409 and 410 through switch 402, which, in normal operation of the machine, is closed.

Also mounted on the shaft 183 is a lever 420 supported by a pivot pin 421. One end of this lever is connected to the sliding core bar of the solenoid as at 423. At the other end of the lever is a downwardly directed block 425. An arm 426 also extends from the shaft 183 to a position along side of the lever below the block. Also, it will be observed by reference to Fig. 16 that there is a cam like projection 430 on the end surface of the hub portion 190a of gear wheel 190.

In normal operation of the machine the switch 402 is closed and thus the circuit to the solenoid is closed and the core is drawn to a position so that the lever 420 is in a position free and clear of the hub or wheel 190. However, in the event of a jam, or entrance of a damaged sheet into the 75

- machine, the switch 402 will be opened and this opens the circuit through the solenoid 413 to permit the core bar to slide upwardly and the block at the end of lever 420 to drop down between the lever arm 426 and end of the wheel hub. The cam 430 on the wheel hub then engages the block and pushes the lever laterally against arm 426 thereby rotating the shaft 183 to cause the clutch 181 to be released to stop the machine.
- With the machine so constructed, it is apparent that the sheets of tin placed on the elevator may be automatically fed into the machine, cut into strips, then the strips divided in pieces of can body size. The entire operation will be automatic and under automatic control so that high speed production is possible without danger of damage to machinery in the event of jams.
- Having thus described our invention, what we claim as new therein and desire to secure by Letters Patent is—
1. In a machine of the character described, the combination with sheet cutting devices and means for conveying sheets of material to said devices of means for supporting a stack of sheets to be cut, a traveling conveyor operating across the top of the stack toward the cutters, feed mechanism operable to partly lift the sheets one at a time from the top of the stack for engagement by the conveyor for conveyance thereby to the cutters, and mechanism automatically operable to adjust the stack supporting means to the feed mechanism in accordance with removal of sheets from the stack.
  2. In a machine of the character described, the combination with sheet cutting devices of a supporting table for a stack of sheet material to be cut, a traveling conveyer having sheet moving devices thereon for effecting the movement, in succession, of sheets from a stack on said table to the cutting devices, feed devices operable to cause sheets to be partly lifted, one at a time, from the top of the stack for engagement by said sheet moving devices of the conveyer for movement thereby to the sheet cutting devices and mechanism operable automatically to adjust the stack supporting table to the feed devices in accordance with removal of sheets from the stack.
  3. In a machine of the character described, in combination, a series of sheet cutting devices, a supporting table for a stack of sheet material, a conveyer operating across the table and having devices thereon for moving the sheets successively from the stack to the sheet cutting devices, reciprocally acting suction devices synchronized with the conveyer movement and operable against the top of the stack to lift the sheets, one at a time, from the top of the stack to position for engagement by said sheet engaging means of the conveyer and means for automatically adjusting the stack supporting table upwardly in accordance with removal of sheets from the stacks.
  4. In a machine of the character described, in combination, a series of sheet cutting devices, a supporting table for a stack of sheet material to be cut, a conveyer belt operable across the table, sheet engaging lugs on the belt for moving the sheets, one at a time, from the stack to the cutting devices, hold down members overlying the stack of sheets and spaced from the belt at opposite sides thereof, sheet lifting devices reciprocally movable between said members and operable against and upwardly from the stack to lift the top sheet to an upwardly bowed position between the hold down devices to position for engagement by one of the sheet engaging lugs of the conveyer belt for movement thereby to the cutting devices.
  5. In a machine of the character described, in combination, a series of sheet cutting rolls, a supporting table for a stack of sheet material to be cut, a guideway between the stack and cutting rolls, a conveyor belt operating across the stack and along the guideway, sheet engaging devices on the belt for moving the sheets from the stack along the guideway to the cutting rolls, a pair of hold down rollers overlying the stack spaced from the opposite sides of the conveyer belt, suction devices reciprocally movable between said rollers against and from the stack to lift the top sheet against the rollers and to bow it upwardly between them to position suitable for engagement by one of said sheet engaging devices of the conveyer belt and means automatically operable to adjust the stack supporting means upwardly in accordance with removal of sheets from the stack.
  6. In a machine of the character described, in combination, a series of sheet slitting rolls, means for supporting a stack of sheets to be cut, a guideway between the supporting means and slitting rolls, a conveyer operable to deliver sheets in succession from the stack to the slitting rolls along the guideway, said guideway comprising a fixed squaring up rail at one side against which a side edge of each sheet may be abutted in its advancement to the slitting rolls, a guide rail at the opposite side, parallel with the first rail and movable from and toward it to accommodate sheets of different width and means applying an inward pressure against the latter rail to urge it against the sheet and to retain the latter against the fixed rail and squared relative to the slitting rolls.
  7. In a sheet trimmer and slitter, in combination, a pair of parallel arbors, sheet slitting rolls cooperatively arranged thereon, a table, a guideway on the table within which sheets may be advanced to the rolls, and means for delivering sheets along the guideway; said guideway comprising a fixed squaring up rail at one side, a pressure rail at the other side movably mounted for automatic inward or outward adjustment to accommodate sheets of different widths, means for urging the pressure rail inwardly, a lead in section at the entrance of the guideway extending from the pressure rail in an outwardly inclined direction as a sheet directing guide and movable by contact of entering sheets to accommodate its position to passage of sheets of different widths, and means connecting the lead in section with the pressure rail whereby movement of the former will effect a corresponding adjustment of the pressure rail.
  8. In a machine of the character described, a series of sheet slitting rolls arranged to receive sheet material therebetween to cut it into strips, a guideway extending across the path of delivery of said strips from the said rolls to receive the strips transversely thereof, a conveyer operating lengthwise within the guideway and having strip engaging lugs therein at spaced intervals, and means extending across the guideway for the support of the forward edge portions of the strips as delivered from the slitting rolls and whereby the rearward edge portions of the strips will drop first into the guideway for engagement and advancement in spaced relation by successive lugs of the conveyer.
  9. In a machine of the character described, a series of sheet slitting rolls, means for delivering

sheet material to said rolls to be cut into strips thereby, a guideway extending transversely of the path of delivery of strips from the slitting rolls and at a lower level, a conveyer operating lengthwise of the guideway lugs on the conveyer at spaced intervals greater than the width of the strips for forwarding strips along the guideway, rods extended across the guideway to support the forward edges of the strips in their delivery across the guideway from the slitting rolls, and permitting the rear edges of the strips to drop first onto the guideway when released from the rolls for advancement and spacing by the conveyer lugs and a series of cutting rolls arranged across the delivery end of the said guideway for dividing the strips transversely.

10. In a machine of the character described, a series of sheet slitting rolls, means for feeding sheet material to said rolls to be cut in strips thereby, a guideway arranged to receive the strips transversely thereof, a series of strip dividing cutters disposed across the delivery end of the guideway, a conveyer operating lengthwise of the guideway for advancing the strips in succession to a position near the dividing cutters, feed bars reciprocally operable to advance the strips, as brought to position by the conveyer, into the dividing cutters.

11. In a machine of the character described, a series of sheet slitting rolls, means for feeding sheet material to said rolls to be cut in strips thereby, a guideway arranged to receive the strips transversely thereof, a series of strip dividing cutters disposed across the delivery end of the guideway, a conveyer operating lengthwise of the guideway for advancing the strips in succession to a position near the dividing cutters, feed bars at opposite sides of the guideway reciprocally operable in unison and having feed fingers therein to engage the strips to successively deliver them as brought to position by the conveyer, to the dividing cutters, and means arranged to frictionally engage the strips intermediate the ends to retain them firmly against the feed fingers while being advanced by the feed bars.

12. In a machine of the character described, a pair of parallel arbors, a series of sheet cutting rolls cooperatively arranged in spaced relation on the arbors, a guideway leading to the rolls, means for delivering strips of material in succession along the guideway to a position adjacent the arbors, feed slides reciprocally operating in unison at opposite sides of the guideway, fingers on said slides in parallel alignment with the arbors for engaging the rear edges of the strips to advance them into the cutting rolls and means for bearing frictionally against each strip intermediate its ends while being advanced by the feed fingers to retain it firmly against the feed fingers and thereby in parallel relation with the arbors.

13. In a machine of the character described, a pair of parallel arbors, a series of sheet cutting rolls cooperatively arranged thereon, a guideway leading to the rolls, means for delivering strips of sheet material into the guideway transversely thereof, means for advancing the strips in succession along the guideway and for delivering them to the cutting rolls, said guideway having a fixed positioning rail at one side, and means for causing said strips to be moved into end abutment with said rail for delivery to said cutters.

14. In a machine of the character described, a pair of parallel arbors, a series of sheet cutting

rolls cooperatively arranged in spaced relation thereon, a guideway leading to the rolls, means for delivering strip material into the guideway, means for advancing the strips in succession along the guideway to said rolls, feed devices for delivering the strips between the rolls parallel with the arbors, a fixed strip positioning rail at one side of the guideway adjacent the cutters and means for engaging each strip to hold it in end abutment with said rail as the strip is advanced to the cutters.

15. In a machine of the character described, a pair of parallel arbors, a series of sheet cutting rolls cooperatively arranged in spaced relation thereon, a guideway leading up to the rolls, means for delivering strip material into the guideway, means for advancing the strips in succession along the guideway to said rolls, feed devices for delivering the strips between the rolls parallel with the arbors, a fixed strip positioning rail at one side of the guideway adjacent the cutters and a reciprocating member synchronized with the feed devices and having a yieldable abutment thereon engageable with the end of each strip to push it into end abutment with said positioning rail as it is advanced to the cutters.

16. A sheet trimmer and slitter comprising a pair of arbors with a series of cutting rolls arranged thereon in cooperating relation, means for delivering sheets of material in succession to said rolls to be cut thereby into strips of equal width, a second pair of arbors, a series of cutting rolls arranged cooperatively thereon, a guideway arranged to receive the strips as delivered from the first series of cutters, means for advancing the strips in succession along the guideway to the second series of cutters and for passing them through the cutters parallel with the arbors whereby the strips are cut into pieces of equal length.

17. A sheet trimming and slitting machine comprising a pair of parallel arbors, with a series of cutting rolls arranged cooperatively thereon, means for supporting a stack of sheet material, a guideway leading to the cutting rolls, means for feeding sheets from the stack to the guideway and for delivering them in succession to the rolls to be cut thereby into strips of equal width, a second pair of arbors extending at right angles relative to the first set, a series of cutting rolls arranged in cooperative relation thereon, a guideway arranged to receive the strips as delivered from the first series of rolls, means for advancing the strips in succession therealong to the second series of cutters and for delivering them thereto with their side edges parallel with the arbors, whereby the strips are cut into pieces of equal length; each of said guideways having a fixed positioning rail at one side, means associated with the first guideway for yieldably holding the sheets against the positioning guide as they are advanced to the cutters, and means associated with the second guideway whereby each strip is moved into end abutment with the positioning guide as they are delivered to the cutters.

18. In a machine of the character described, a main frame, a series of sheet cutting rolls, means for supporting a stack of sheet material, a guideway along which sheets may be moved from the stack to the cutting rolls, a second frame normally overlying the stack supporting means and the guideway, and feed mechanism mounted by the second frame and operable for the delivery of sheets in succession from the stack to the sheet cutting rolls along the guideway; said second

frame being hingedly attached to the main frame and adapted to be raised from normal position clear of the guideway and stack.

19. In a machine of the character described, 5 the combination with a series of cutters, means for supporting a stack of sheet material, a guideway between the stand and cutters, feed devices and a conveyer for the delivery of sheets from the stack to the cutters and a driving mechanism for 10 the feed device and conveyer, of means operable to automatically disrupt the driving mechanism from said parts incident to an abnormal delivery of sheets along the guideway.

20. In a machine of the character described, a 5 pair of parallel arbors, a series of cooperating cutters on said arbors, a guideway, reciprocating feed slides operable against opposite end portions 10 of the strips disposed in the guideway to push

them into the cutters, parallel with the arbors, and a friction device adapted to bear against the strips as advanced by the slides.

21. In a machine of the character described, a 5 series of cutters, means for supporting a stack of sheet material, a guideway between the stack and cutters, a conveyor for delivery of sheets along the guideway in succession from the stack to the cutters, a driving mechanism for the conveyor including a releasable clutch, pivotally 10 mounted arms overlying the guideway for passage of the sheets beneath them, a solenoid controlling the clutch, a circuit for the solenoid and a switch in the circuit under control of said pivoted arms. 15
